P. COMPTON.
ADVERTISING DEVICE.
APPLICATION FILED JUNE 5, 1916.

1,212,741.

Patented Jan. 16, 1917.

PAUL COMPTON,
Knight & Cook 9740

UNITED STATES PATENT OFFICE.

PAUL COMPTON, OF ST. LOUIS, MISSOURI.

ADVERTISING DEVICE.

1,212,741.

Specification of Letters Patent. Patented Jan. 16, 1917.

Application filed June 5, 1916. Serial No. 101,763.

To all whom it may concern:

Be it known that I, PAUL COMPTON, a citizen of the United States of America, a resident of the city of St. Louis, State of Missouri, have invented certain new and useful Improvements in Advertising Devices, of which the following is a full, clear, and exact description, reference being had to the accompanying drawing, forming a part of this specification.

My invention relates to an advertising device, particularly adapted for use in stores by displaying the device in show windows, upon store counters, or other convenient places.

The preferred form of the invention is a sign or display device, made of sheet material and adapted to be folded so as to occupy a very small space when not in use.

One of the objects of the invention is to produce a simple, inexpensive and attractive advertising device of this kind comprising a plurality of sections arranged one above the other, the lower section constituting a substantial base or supporting element for the other members of the device.

Another object is to provide an inexpensive means for retaining all of the foldable members in their unfolded condition.

Figure I is a front elevation of my advertising device, showing the parts unfolded. Fig. II is a top view of the device as it appears when unfolded. Fig. III is a rear view, on a smaller scale, of the device shown in Figs. I and II. Fig. IV illustrates the device in its folded condition.

All of the elements of the device I have shown are made of a single piece of cardboard, or other sheet material.

A designates a substantially V-shaped display base section, comprising a pair of diverging display board members 1, hinged to each other at 2, the hinge being formed by folding or scoring the base section on the central line of the device.

B designates a foldable display upper section extending across the base section and connecting the diverging board members 1. The upper display section comprises a pair of display board members 3 and 3' hinged to each other at 4. This hinge is formed by scoring or folding the upper display section on the central line of the device. The hinges 2 and 4 are parallel with each other, but the

axis of the hinge 4 lies in a vertical plane at 55 the rear of the hinge 2.

The diverging display board members of the base section are provided with vertical extensions 5 and 5', and the upper display board members 3 and 3' are hinged to the vertical edges of these extensions. The hinge 6, at one of the vertical edges, may be formed by merely scoring the cardboard blank at the junctions of the upper member 3 and the extension 5, but to produce the device I have shown, it is necessary to remove some of the material from the blank at a point between the vertical edge of the extension 5' and the adjacent edge of the board member 3'. The upper member 3' is, therefore, provided with a flap 7 (Figs. II and III), said flap being cemented to the extension 5', and a hinge 6' being formed by scoring the blank at the junction of the flap 7 and the upper board member 3'. 75

When the device is unfolded, the upper display section B extends in a straight line across the base section A, as shown most clearly in Fig. II, the straight upper section being in a vertical plane at the rear of the apex of the base section. In folding the device, the diverging members 1 of the base section are moved toward each other, as indicated by arrows in Fig. II, and during this movement, the members 3 and 3' of the upper section are moved toward each other on the axis of the vertical hinge 4, at the same time turning on the axes of the hinges 6 and 6'. When the article is folded to the condition shown in Fig. IV, it is absolutely 90 flat, and its thickness is equal to about twice the thickness of the sheet material. When unfolded, the V-shaped base section constitutes a substantial support for the straight upper section, and the two sections are combined with each other to produce a neat and attractive advertising sign. 95

To retain all of the elements in their unfolded positions, the upper display section is provided with a retaining flap F, said flap 100 being hinged to the lower edges of the upper sections 3 and 3', and the axis of its hinge being at a right angle to the axis of the vertical hinge 4. When the retaining flap F is folded backwardly, to the position shown in 105 Figs. II and III, it prevents the upper members 3 and 3' from turning on their hinge 4, and since all of the other foldable elements

are secured to these upper members, it will be apparent that the retaining flap F will rigidly secure all of the elements in their unfolded positions.

5 I claim:—

1. In a foldable device of the character described, a base section provided with diverging board members, said diverging board members being hinged together and 10 having rear vertical extensions, and an upper board section extending across said base section, the vertical extensions of the diverging board members of the base section being hinged to said upper board section.
- 15 2. In a foldable device of the character described, a substantially V-shaped base display section comprising a pair of board members hinged to each other at the front of the device, and an upper display section 20 extending across said substantially V-shaped base section and hinged to each of said board members, said upper section comprising a pair of board members hinged together at a point to the rear of the apex of 25 the base section.
- 30 3. In a device of the character described, a foldable base section comprising diverging board members, a foldable upper section extending across said base section, said upper section comprising board members hinged to each other and secured to the diverging board members of the base section, and means for preventing the board members of the upper section from turning on 35 their hinge, thereby retaining all of said board members in their unfolded positions.
- 40 4. In a foldable device of the character described, a base section, an upper section supported by said base section, said upper section including board members hinged to each other; and a retaining flap hinged to said board members, said retaining flap be-

ing adapted to lie at an angle to the axis of the hinge of the board members so as to retain the device in its unfolded condition.

45

5. In a device of the character described, a foldable base section comprising diverging board members, a foldable upper section extending across said base section, said upper section comprising board members 50 hinged to each other and secured to the diverging board members of the base section, and means for preventing the board members of the upper section from turning on their hinge, thereby retaining all of said 55 board members in their unfolded positions, said means including a flap secured to said upper section at points on opposite sides of the axis of the last mentioned hinge and adapted to lie at an angle to said axis.

60

6. In a foldable advertising sign of the character described, a V-shaped base section comprising a pair of diverging board members hinged to each other at the apex of the base section, an upper section extending 65 across said V-shaped base section, the diverging board members of the base section being provided with vertical extensions and the upper section being hinged to the vertical edges of said extensions, said upper 70 section comprising a pair of upper board members hinged to each other at the center line of the device at a point to the rear of the apex of the V-shaped lower section, and a foldable retaining flap hinged to the lower 75 portions of the pair of upper board members in the plane of the axis of the hinge uniting said upper members, said retaining flap being foldable backwardly to lie at an angle to the axis of the last mentioned hinge so 80 as to secure all of said members in their unfolded positions.

PAUL COMPTON.
